RUG MAKING DEVICE

Benjamin Mayer, Brooklyn, N. Y.

Application March 10, 1938, Serial No. 194,985

7 Claims. (Cl. 28—15)

The invention relates to improvements in apparatus for making rugs and the like and has for its primary object the provision of a simple and efficient apparatus having means for quickly and efficiently producing rugs by hand.

An object of this invention is to provide a hand made form of hooked rug imitative of chenille or the like and a loom device and method of making the same.

Another object is the provision of improved portable apparatus capable of being used independent of other machinery and particularly in the home or the like of a user by means of which small lengths of yarn, thread wool, or cloth or the like may be utilized to form the face of the rug.

Still another object is the provision of mechanism in such device for holding in place the balls of cord to which are bound the small lengths of yarn; said ball holder having means for locking a strand of cord, of the ball, thereto, or for locking a plurality of strands of a plurality of balls separately thereto.

These and other objects will be readily understood from the following description and drawings.

In the drawing,

Fig. 1 is a perspective view of the preferred form of loom device.

Fig. 2 is a fragmentary view of the cord locking portion of the device showing same in upper and turned position relative to its mounting shafts.

Fig. 3 is a sectional elevation along line 3—3 of Fig. 1, of an embodiment having means for mounting and operating a plurality of balls of cord and their respective strands.

Fig. 4 is a fragmentary top plan view of an embodiment having the cord lock means separate and forwardly of the cord ball retainer.

Fig. 5 is a fragmentary view of a plurality of bound wool elements produced on the device of Fig. 1.

Fig. 6 is a fragmentary view of a plurality of bound wool elements produced on the structure of Fig. 3.

Fig. 7 is an enlarged sectional view taken on line 7—7 of Fig. 1.

A flat base frame 10, Fig. 1, suitably shaped and preferably formed of a single piece of wire, has mounted between frame sides 107, 108, parallel with frame ends 101, a cross member 11, which in turn has mounted thereon upright shafts 12, 13, and 14. Shafts 12 and 14 provide means for rotatable mounting on each thereof, of a ball of preferably multi strand cord or wool 30, 40, or

the like. Shaft 13, having upper stop 131, has pivotally mounted thereon, cord cover frame member 15, preferably as shown. A flat piece of spring metal 151, closely fastened to the upper part 159 of 15 and flexing normally towards 159, and having raised ends 152 for ready insertion of cord 301 thereunder, provides an automatic spring lock means to grasp and hold said cord 301, 401, between it and member 159. Said cords are thence tied together at their loose ends 307 and removably hooked or looped to hook 16, in turn mounted on frame end 101.

It is seen that member 15 may be raised to about stop 131, Figs. 1 and 2, and thence turned about 13, from the ends of shafts 12 and 14 to thus permit removal or mounting of balls 30 and 40. When the cord cover is in operative position, as in Fig. 1, the upper ends of 12 and 14 abut the under side of 159 determining the lowest position of 15 and it thus acts as a cover stop preventing the accidental removal of mounted balls 30 and 40, as shown.

Fig. 3 discloses an elevation of an embodiment having a plurality of automatic cord spring lock members, 151, mounted on said cord cover and also providing means for the multiple deck mounting of a plurality of balls of cord 30 and 40, and for guiding (see guide 70) the respective cords of said balls as is clear to one skilled in the art.

Fig. 4 shows, in plan view, an embodiment in which the cord spring lock is permanently mounted forward of the balls 30 and 40 which balls are retained on suitable shafts 12 and 14, mounted noninterferingly with the spring lock and having cover piece 20, thereover. Thus the rear end of a spent ball of cord may be fastened to the forward end of the following ball without disturbing the cord lock grasp of the rear end portion of the spent ball. This embodiment presents means for more orderly workmanship in the weaving operation by preventing entanglement of unlocked spent cord ends which entanglement is possible in the structure of Fig. 1, at the time for placing a new ball on shafts 12 and 14, which ball end may be connected to the rear end cord portion of the spent ball.

In Figs. 1 and 7, is shown the preferred method of attaching or binding a short length of wool or cloth (about 2 inches) 50, to the cords 301, 401. The short wool cord is preferably first placed across the top of said cords, as at 80, and the ends of the wool are directed downwardly and around the cords and brought thence upward forwardly of aforementioned portion lying across the cords.

The wool ends are thence pulled upwardly and the formed loop tightened forming a two strand element 19, Fig. 7. Said element is thence slid forwardly on the cords toward the operator at 5 end 101, toward hook 16, to abut the previously formed loop. While I have shown the method of binding a length of wool thread to cords 301 and 401, it is obvious that while operating the device of Fig. 3, any two cords such as 302 and 301, or 10 403 and 303, may be bound to each other by the short length of wool and that in this manner a plurality of elements 19 may be formed. By staggering the loops formed by members 50 to the various cords so that successive loops are made to 15 different cords, a plurality of cords are bound to each other forming a multiple stranded element 191, Fig. 6, which is relatively wider than element 19, the aforementioned two stranded element.

When the element 19 is of sufficient length it 20 may be flat wound to produce any shape of rug the length and width of rug formed depending on the length of 19. In said winding the parallel edgewise abutting portions of element 19, are preferably progressively increased in length out- 25 wardly from an inner starting point.

Parts may be used without others and the disclosure is intended to be illustrative rather than limitative.

I claim,

30 1. In a machine of the class described, the combination of a flat base frame formed of one piece of wire, said base having a cross member therewith having three upright shafts, two of said shafts having means for rotatably mounting 35 on each thereof a ball of yarn, the third shaft having rotatably mounted thereon a cover for said balls, said cover having means engageable with the upper portion of said two shafts to engageably hold the cover and said rotatable balls on said shafts, said cover also having locking means on its top for locking a strand of yarn from each of the balls thereto, and a hook at 40 one end of said base frame, relatively lower than said lock, for fastening the end of said yarn strand thereto, whereby a length of yarn may be held taught between said lock and hook so as to slope downwardly toward said hook.

2. In a machine of the class described, the combination of a flat base frame formed of one piece of wire, said base having a cross member therewith having three upright shafts, two of said shafts having means for rotatably mounting on each thereof a ball of yarn, the third shaft having rotatably mounted thereon a cover for said balls, said cover having means engageable with the upper portion of said two shafts to engageably hold the cover and said rotatable balls on said shafts, said cover also having locking means on its top for locking a strand of yarn from each of the balls thereto, said means being a flat elongated spring means having opposite ends normally flexing towards the cover, and a hook at one end of said base frame, relatively lower than said lock, for fastening the end of 55 said yarn strand thereto, whereby a length of yarn may be held taught between said lock and hook so as to slope downwardly toward said hook.

3. In a machine of the class described, the combination of a flat base frame formed of one piece of wire, said base having a cross member therewith having three upright shafts, two of said shafts having means for rotatably mounting on each thereof one or more balls of yarn, the third shaft having rotatably mounted thereon a

cover for said balls, said cover having means engageable with the upper portion of said two shafts to engageably hold the cover and said rotatable balls on said shafts, said cover also having locking means on its top for locking a strand of yarn from each of the balls thereto, said means being a plurality of flat elongated springs mounted one upon another each having opposite ends normally flexing towards the cover, said springs being each respectively shorter in length than its next lower abutting spring, and a hook at one end of said base frame, relatively lower than said lock, for fastening the end of said yarn strand thereto, whereby a number of lengths of yarn may be held taught between said locks and hook 15 so as to slope downwardly toward said hook.

4. In a machine of the class described, the combination of a flat base frame formed of one piece of wire, said base having a cross member therewith having three upright shafts, two of said shafts having means for rotatably mounting on each thereof one or more balls of yarn, the third shaft having rotatably mounted thereon a cover for said balls, said cover having means engageable with the upper portion of said two shafts to engageably hold the cover and said rotatable balls on said shafts, said cover also having locking means on its top for locking a strand of yarn from each of the balls thereto, said means being a plurality of flat elongated springs mounted one upon another each having opposite ends normally flexing towards the cover, said springs being each respectively shorter in length than its next lower abutting spring, and a hook at one end of said base frame, relatively lower than said lock, for fastening the end of said yarn strand thereto, whereby a number of lengths of yarn may be held taught between said locks and hook 20 so as to slope downwardly toward said hook.

5. In a machine of the class described, the combination of a flat base frame formed of wire, said base having a rear cross member therewith having three upright shafts, two of said shafts having means for rotatably mounting on each thereof a ball of yarn the third shaft having rotatably mounted thereon a cover for said balls, said cover having means engageable with the upper portion of said two shafts to engageably hold the cover and said rotatable balls on said shafts, means forward of said shafts for locking a strand of yarn from each of the balls thereto, and a hook at one end of said base frame, relatively lower than said lock, for fastening the end of 55 said yarn strand thereto, whereby a length of yarn may be held taught between said lock and hook so as to slope downwardly toward said hook.

6. In a strand forming device of the class described comprising a flat base frame of one piece 60 of wire, spaced ball twine supporting spindles mounted on one end of said frame, a third spindle mounted intermediate said twine supporting spindles, a removable cover mounted on said third spindle, for said twine spindles and twine tensioning means supported by said third spindle.

7. In a strand forming device of the class described comprising a flat base frame of one piece of wire, spaced ball twine supporting spindles mounted on one end of said frame, a third spindle 70 mounted intermediate said twine supporting spindles, and a removable cover for said twine spindles mounted on said third spindle.

BENJAMIN MAYER.
